[57] CLAIM

The ornamental design for open hood for a gondola car,
as shown.

DESCRIPTION

FIG. 1 is a top perspective view of an open hood for a
gondola car showing my new design;
FIG. 2 is an end elevational view;
FIG. 3 is a top plan view;
FIG. 4 is a side elevational view; and
FIG. 5 is a bottom plan view thereof;
FIG. 6 is a top plan view showing a modified form of
my new design;
FIG. 7 is a side elevational view;
FIG. 8 is an end elevational view; and
FIG. 9 is a bottom plan view thereof.

FIG. 4

FIG. 5

FIG. 6

FIG. 7

FIG. 8

FIG. 9
